UNITED STATES PATENT OFFICE.

HARRY W. OLNEY, OF COLFAX, WASHINGTON.

RULER.

1,208,631.

Specification of Letters Patent. Patented Dec. 12, 1916.

Application filed January 18, 1916. Serial No. 72,714.

To all whom it may concern:

Be it known that I, HARRY W. OLNEY, a citizen of the United States, and a resident of Colfax, in the county of Whitman and State of Washington, have invented certain new and useful Improvements in Rulers, of which the following is a specification.

My invention is an improvement in rulers, and the invention has for its object to provide a device of the character specified, wherein a plate or strip is provided having a scale on one face and provided at the other face with means for supporting a strip of blotting paper in spaced relation with respect to the adjacent face of the plate, to permit the easy application of the blotter to the surface to be blotted.

In the drawings: Figure 1 is a top plan view of the improved ruler; Fig. 2 is a longitudinal vertical section; Fig. 3 is a section on the line 3—3 of Fig. 2; Fig. 4 is a perspective view of the support and the holding means separated, and Fig. 5 is a section on the line 5—5 of Fig. 4, looking in the direction of the arrows adjacent to the line.

In the present embodiment of the invention, a strip 1 of resilient and flexible material is provided, as for instance, steel or the like, and said strip has upon one face and near one edge a series of graduations forming a scale 2. At the opposite face the strip is provided near each end with a socket or holder, each socket or holder comprising a body 5, side flanges 6, and an end flange 7. The free edges of the flanges 6 and 7 are in the same plane, and in a plane inclined to the body 5. Thus the flanges 7 are of the least height, and each flange 6 at its connection with the flange 7 is of the same height and gradually increases in height toward the opposite end of the body. The body 5 of each socket or holder is of less length than the width of the strip 1, and the free edges 45 of the flanges 6 and 7 are secured to that face of the strip 1 remote from the scale 2. The sockets are arranged with their open faces inward, and with the flanges 7 at the ends of the strip 1, as shown more particularly in Fig. 2.

A metal strip comprising a body 8 and angular lugs 9 is connected to the strip 1, with the body 8 of the strip spaced apart from the strip 1 and parallel therewith, and with the lugs 9 engaged within the sockets 5, 6 and 7. The strip 8—9 is secured to the strip

1 by means of a rivet 10, the said rivet engaging registering openings 11 and 12 in the two strips. The ends of the rivet are headed, as shown, to retain the parts in position, and the arrangement is such that the lugs 9 are in contact with the bodies 5 of the sockets at their outer ends, but are spaced apart therefrom at their inner ends.

A series of superposed filling strips 12 is arranged between the strips 1 and 8—9, the said strips being held in place by the rivet 10, and the strips are of such length that they will contact at their ends with the lugs 9 and strip 8—9. Thus a support is provided for the blotter strip, which is held between the socket body 5 and the lugs 9. This support, while sufficiently rigid to cause the blotter to properly blot, is yet yielding to a certain extent.

The blotter strip indicated at 13 is of a width corresponding to the width of the strip 8—9, and is arranged on the outer face of the strip, and this strip 8—9 is resilient to a certain degree, and there is sufficient clamping action between the sockets and the lugs 9 to hold the blotter strip in place.

It will be noticed that the ends of the strip 13 are bent at an angle as indicated at 14, and pass between the bodies of the sockets 8—9 and the lugs 9 of the strip 8—9. This strip 8—9 is secured to the strip 1 by the rivet 10, which also clamps the filling strips 12 in place.

I claim:

1. A blotter comprising a supporting strip of resilient material having at each end of one face a pocket or socket, the said pockets or sockets having their inner ends open, and that wall of each socket remote from the supporting strip inclining away from the adjacent face of the strip toward the inner end of the socket, a strip of resilient material connected to the supporting strip intermediate the ends of the said strips, the resilient strip having at each end an angular portion approximately parallel with the inclined wall of the adjacent socket for clamping the end of a strip of blotting material between the said portion and the inclined wall of the adjacent socket, and filling strips arranged between the resilient strip and the supporting strip.

2. A blotter comprising a supporting strip of resilient material having at each end of one face a pocket or socket, the said pockets or sockets having their inner ends

open, and that wall of each socket remote from the supporting strip inclining away from the adjacent face of the strip toward the inner end of the socket, and a strip of resilient material connected to the supporting strip intermediate the ends of the said strips, the resilient strip having at each end an angular portion approximately parallel with the inclined wall of the adjacent socket for clamping the end of a strip of blotting material between the said portion and the inclined wall of the adjacent socket.

3. A blotter comprising a supporting strip having at each end of one face a pocket, the said pockets having their inner ends open and that wall of each pocket remote from

the strip inclining away from the adjacent face of the strip toward the inner end of the pocket, and a second strip connected to the supporting strip intermediate the ends of the said strips, and having at each end an angular portion approximately parallel with the inclined wall of the adjacent socket for clamping the end of a strip of blotting material between the said portion and the inclined wall of the socket, and filling means between the strips. 20 25

HARRY W. OLNEY.
